DESIGN FOR A JEWELRY BOX OR SIMILAR CONTAINER

John M. Shields, Chicago, Ill., assignor to F. H. Noble & Co., Chicago, Ill., a corporation of Illinois

Application November 11, 1936, Serial No. 65,835

Term of patent 7 years

To all whom it may concern:

Be it known that I, John M. Shields, a citizen of the United States, residing at Chicago, in the county of Cook, State of Illinois, have invented a new, original, and ornamental Design for a Jewelry Box or Similar Container, of which the following is a specification, reference being had to the accompanying drawing, forming a part thereof.

In the drawing, Figure 1 is a perspective view of a jewelry box embodying my new design, with the cover in closed position;

Fig. 2 is a similar perspective, with the cover raised;

Figs. 3 and 4 are, respectively, front and side elevations of the box; and

Fig. 5 is a plan view of the same.

I claim:

The ornamental design for a jewelry box or similar container, as shown.

JOHN M. SHIELDS.
